UNITED STATES PATENT OFFICE

153,055

DESIGN FOR A HOUSEHOLD WEIGHING
SCALE

Vytant Aleks, Rockford, Ill., assignor to The
Brearley Company, Rockford, Ill., a corporation
of Illinois

Application December 6, 1947, Serial No. 143,008

Term of patent 7 years

(Cl. D52—10)

To all whom it may concern:

Be it known that I, Vytant Aleks, a citizen of the United States, residing at Rockford, in the county of Winnebago and State of Illinois, have invented a new, original, and ornamental Design for Household Weighing Scale, of which the following is a specification, reference being had to the accompanying drawing, forming part thereof.

In the drawing:

Fig. 1 is a front view of a household weighing scale, showing my new design;

Fig. 2 is a side view, and

Fig. 3 is a plan view.

I claim:

The ornamental design for a household weighing scale, as shown.

VYTANT ALEKS.
